UNITED STATES PATENT OFFICE.

PAUL WOITYNEK, OF LA SALLE, ILLINOIS.

MAIL-BAG APPARATUS

No. 894,302.

Specification of Letters Patent.

Patented July 28, 1908.

Application filed April 20, 1908. Serial No. 428,113.

To all whom it may concern:

Be it known that I, PAUL WOITYNEK, a citizen of the United States, residing at La Salle, in the county of Lasalle and State of Illinois, have invented certain new and useful Improvements in Mail-Bag Apparatus; and I do declare the following to be a full, clear, and exact description of the invention, such as will enable others skilled in the art to 10 which it appertains to make and use the same.

This invention relates to new and useful improvements in receiving and delivering apparatus for mail bags and has for its principal object the production of a suitable car adapted to travel on an overhead or trolley track in which the mail bag or bags may be placed to be delivered into the mail car of the passing train or from the mail car of the 20 train to the station.

A secondary object of the invention resides in the provision of means for positively retaining the car hook in engaged relation with the mail car until released by the attendant in the mail car of the train.

With the foregoing and other objects in view, the invention consists of certain novel features of construction, combination and arrangement of parts, as will be more fully 30 described and particularly pointed out in the appended claims.

In the accompanying drawings:—Figure 1 is a view in side elevation of the delivery apparatus, the car or carrier in mail delivery, 35 or receiving position with parts of the overhead track broken away. Fig. 2 is a similar view on an enlarged scale of the car or carrier and a section of the track, and, Fig. 3 is a cross section taken on line 3—3 of Fig. 2, 40 looking in the direction indicated by the arrows.

In the embodiment illustrated, the overhead track 1 consists of two series of vertically spaced track wires 2, one series being 45 spaced laterally with respect to the other series. The numeral 3 denotes a car, the frame 4 of which is of any desired pattern or structure adapted to suitably support supporting wheels 5, designed to travel between 50 the vertically spaced track wires, two of the wheels being arranged at one side of the car and two at the opposite side of the car.

A longitudinally projecting upwardly inclined arm 6 is arranged at each side and end 55 of the car frame, and to the outer ends of

these arms are journaled suitable wheels 7 of relatively small dimensions, designed to travel on the upper track wires slightly in the rear and in advance of the supporting wheels 5 to retain said wheels in proper position, 60 that is to say, to avoid liability of the wheels jumping or leaving the track.

A secondary series of longitudinally projecting downwardly inclined arms 8 are also arranged below the first mentioned series and at the ends of the arms 8 are journaled guide wheels 9 adapted to travel under the lower track wires and which serve to effectually retain the supporting wheels of the car or carrier from jumping or leaving the same. 70

In practice the track wires are supported by upright supports 10 arranged at suitable distances apart. This track may be extended any desired distance beyond the station and the end of the track may be suitably 75 inclined to cause the car or carrier to return to its normal position after having been released by the car. A suitable buffer, not shown, may also be arranged at the end of the track to absorb violent shocks or strains 80 which would otherwise be induced in the car incident to a sudden stoppage of the same, when reaching the end of the track.

A basket 11 preferably of woven wire, is 85 suitably supported below the car or carrier frame to receive the mail bags to be delivered from the station into the mail car of the train or to be delivered at the station.

A particular feature of the invention resides in the provision of yieldable car hook 90 engaging means for effectually retaining the car hook in engaged relation therewith until released by the attendant in the mail car. As shown, said engaging means is made from a single piece of spring metal bent centrally 95 upon itself in the form of a loop 13 and thence extended outwardly in opposite directions at its ends as at 14 to form an outwardly flaring mouth to receive a car hook 15. By this construction, the ends 14 of the 100 engaging device will spring sufficiently apart when engaged by the car hook to permit the same to engage the looped portion thereof. These ends, however, will then immediately 105 spring or return into their normal position and effectually retain the car hook against displacement until released by the attendant in the mail car.

From the foregoing description taken in connection with the accompanying drawings, 110

the construction and operation of the invention will be readily understood without requiring a more extended explanation.

While I have shown and described the preferred embodiment of the invention, it is to be understood that various changes in the form, proportion and minor details of construction may be resorted to without departing from the principle or sacrificing any of the advantages of the invention.

Having thus fully described my invention, what I claim as new and desire to secure by United States Letters-Patent is:—

1. In an apparatus of the class described, the combination with an overhead track consisting of two series of vertically spaced track wires, of a car or carrier having supporting wheels to travel between said wires, an upper series of longitudinally extending upwardly inclined arms attached to the car frame and projecting in advance and in rear of the supporting wheels, a lower series of longitudinally projecting downwardly inclined arms attached to the car frame and also projecting in rear and in advance of the supporting

wheels, guide wheels attached to the outer ends of said arms in position to travel on the track wires, a suitable receptacle supported below the car frame and car hook engaging means attached to said frame.

2. In an apparatus of the class specified, the combination with an overhead track, of a car or carrier having supporting wheels to travel thereon, a mail bag receptacle supported below the car frame, and car hook engaging means attached to the frame, said means comprising a single element of spring metal bent centrally upon itself to form a looped portion and thence extended outwardly in opposite directions at the ends of the looped portion to form an outwardly flared mouth.

In testimony whereof I have hereunto set my hand in presence of two subscribing witnesses.

PAUL WOITYNEK.
